RAZOR BLADE SHARPENER

Arthur C. Heise and Millard W. Jacobi,
Baltimore, Md.

Application August 8, 1934, Serial No. 739,016

9 Claims. (CL 51—158)

This invention relates to a safety razor having associated therewith improved means for sharpening a razor blade.

One object of the invention is to provide a safety razor wherein the handle is formed with a chamber wherein a sharpening element is mounted and to further provide a blade carrier adapted to be inserted in the chamber and support a blade in operative relation to the sharpening element so that by reciprocating the carrier in the chamber, the blade will be sharpened.

Another object of the invention is to provide the razor with a handle and blade carrier of such construction and dimensions that a blade of proper size to fit the guard of the razor may be applied to the carrier and the carrier and blade then thrust into the handle as a unit and allowed to remain therein until use of the razor is required. By this arrangement, the blade will 20 always be readily accessible when needed and can be sharpened before use.

Still another object of the invention is to so form the handle and blade carrier that when the carrier is thrust into the chamber of the handle, it may be oscillated to dispose the cutting edge of the blade in proper angular relation to a block of abrading material in the chamber and to limit the oscillating movement of the carrier and also guide longitudinal movement of 30 the carrier during reciprocation thereof when sharpening the blade.

A still further object of the invention is to so construct the carrier that when a blade is applied thereto, it will be firmly held in its proper 35 position and caused to move with the carrier.

The invention is illustrated in the accompanying drawings wherein:

Figure 1 is a side elevation of the improved 40 razor;

Figure 2 is a top plan view of the razor; 45 Figure 3 is a section taken longitudinally through the razor along the line 3—3 of Figure 2;

Figure 4 is a view showing the razor with its handle in longitudinal section and the blade 50 holder in top plan, portions of the guard of the razor being broken away;

Figure 5 is an elevation looking at the front 55 end of the razor;

Figure 6 is a view showing the forward portion 50 of the razor partially in top plan and partially in section, the blade securing bar being swung away from the blade holder or shield;

Figure 7 is a section taken along the line 7—7 55 of Figure 3;

Figure 8 is a view similar to Figure 3 showing

the blade carrier partially in section and a blade carried thereby;

Figure 9 is a view somewhat similar to Figure 8 showing the blade carrier partially withdrawn from the handle and illustrating the manner in 5 which the carrier is reciprocated during a sharpening operation;

Figure 10 is a sectional view taken along the line 10—10 of Figure 9;

Figure 11 is a fragmentary sectional view illustrating 10 the manner in which a blade is fitted into the carrier;

Figure 12 is a transverse section taken along the line 12—12 of Figure 9;

Figure 13 is a view similar to Figure 12 illustrating 15 the manner in which the carrier is oscillated in the handle to dispose the blade in proper engagement with the abrading block during a sharpening operation; and

Figure 14 is a perspective view of the blade used 20 with this razor.

This improved razor has a handle 1 formed with a reduced neck 2 at its front end, the extreme forward end of which is further reduced to provide a rivet 3 by means of which a guard 25 or shield 4 is rigidly secured to the handle. The shield is formed of sheet metal and has its upper portion 5 curved rearwardly and downwardly and terminating in a tongue 6 located intermediate the width of the shield and formed with an 30 opening through which the rivet 3 is passed and then headed as shown in Figure 3. The shield or guard is disposed transversely of the handle and has its lower edge portion formed with teeth 7 through which portions of the cutting edge of 35 a blade 8 will be exposed when the blade is applied against the outer or front face of the shield. There have also been provided spurs or tongues 9 located adjacent opposite ends of the lower edge of the shield for engaging under the 40 cutting edge of the blade and supporting the blade when in place.

The blade is to be securely but detachably held in engagement with the shield and in order to do so there has been provided a bar 10 formed 45 from a strip of resilient metal. This bar has one end provided with longitudinally extending tongues which are bent to form loops 11 engaged through slots 12 formed in the shield and serving to pivotally mount the bar for swinging 50 movement from the released position shown in Figure 6 to a clamping position in which it extends across a blade along the backing 8a at the upper edge thereof. The free end portion of the bar is bent to form a bill 14 which snaps 55

over the edge of the shield as clearly shown in Figure 4 and securely but releasably holds the bar in the clamping position. By this arrangement, the blade can be quickly applied to the shield and firmly secured.

Referring to Figures 3, 5 and 7, it will be seen that the blade is narrow and that when it is applied against the guard, the backing 8a is disposed midway the depth of a slot 4a formed longitudinally in the guard. It should also be noted that the backing holds the blade in spaced relation to the front face of the guard to provide a space 13 between the blade and guard extending from the lower cutting edge of the blade to the slot. Therefore, lather and hair which may be forced between the guard and lower edge of the blade during a shaving operation may pass upwardly through the space 13 and out through the slot 4a without choking the razor and preventing the blade from cutting properly. By bowing inwardly the lower portion of the guard, the size of the space 13 will be increased and free passage of the lather and hair permitted. When the blade is to be removed it is merely necessary to spring the latch out of engagement with the shield and the blade can be removed and the razor and blade thoroughly washed.

The handle 1 which is also formed of metal is hollow to provide a chamber 15 opening through the rear end of the handle and by referring to Figures 12 and 13, it will be seen that the handle is elliptical in cross section and has its walls crimped inwardly to provide sets of ribs 16 and 17, the ribs of each set being spaced from each other circumferentially of the handle. An elongated block 18 of honing material extends longitudinally in the chamber 15 and is cemented against walls of the chamber between the ribs 16 which engage opposite side edges of the block and prevent the block from shifting transversely out of its proper position. This block is formed with a groove 19 in its exposed face and referring to Figures 12 and 13, it will be seen that walls of the groove are curved transversely and converge inwardly of the groove in order that the bevelled faces of the blade along its cutting edge may have proper engagement with the abrading block during a sharpening operation.

In order to support the blade in the chamber and impart reciprocating motion to the blade during a sharpening operation there has been provided a blade carrier which is formed of resilient metal. The body portion 20 of the blade carrier is of tubular formation and at its rear or outer end carries a head or finger hold 21 which has its marginal face roughened in order that it may be firmly grasped and is provided with a neck 22 of the proper shape and dimensions to fit snugly within the rear portion of the handle and have frictional gripping engagement with walls of the handle to securely but removably hold the carrier in the chamber of the handle. The tubular body is not circular in cross section but of the configuration shown in Figures 12 and 13 and has an arcuate wall 23 which conforms to the portion of the walls of the handle between the ribs 17 and merges into side walls 24 which are bowed inwardly. A partition or abutment wall 25 blocks the interior of the body intermediate the length thereof and between this partition and its open forward end the body is formed with a longitudinally extending slot 26. The portions of the side walls bordering the slot carry extensions which project inwardly of the tubular body and form grip-

ping jaws 27 the lower edges 28 of which diverge and bear against portions of the backing strip 8a at opposite sides of the blade 8 when the blade is thrust into the holder. When the blade is thrust into place, it is forced inwardly between the jaws from the front end of the body and as it moves rearwardly, it passes between tongues 29 at the front of the body. These tongues extend longitudinally of the body at opposite sides of the slot and have their free ends normally in engagement with each other so that when the blade is in place, the front ends of the tongues will engage each other beyond the outer end of the blade as shown in Figure 10 and prevent the blade from slipping forwardly out of place. The abutment wall 25 prevents the blade from shifting rearwardly of the carrier beyond the position shown in Figure 9 and therefore, the blade will be caused to reciprocate with the carrier during a sharpening operation. Tongues 30 which are struck from the wall 23 of the carrier and extend longitudinally of the carrier engage the backing strip of the blade and hold the blade in its proper position with the backing strip bearing against the flared portions of the jaws and the cutting edge of the blade in engagement with the abrading block.

When this razor is in use the blade is applied to the outer or front face of the guard where it is secured by the bar 10. The lower cutting edge of the blade rests at its ends upon the prongs or tongues 9 and between these prongs is overlapped by the teeth 7 as shown in Figure 7 so that there will be no danger of a person cutting his face while shaving. After the shaving operation has been completed, the bar 10 is released and swung out of the way and the razor thoroughly cleaned. The blade can then be again secured against the guard but it is preferred to withdraw the blade carrier from the handle and fit the blade into the tubular body of the carrier. The carrier is then returned to its initial position within the handle and the blade will be shielded and prevented from being accidentally nicked. When the razor is again to be used, the carrier is grasped by its head 21 and drawn outwardly. After the carrier has been withdrawn a sufficient distance to free the neck 22 from the handle, the carrier can be given a partial rotation in either direction until the carrier abuts one of the ribs 17 and the carrier slid longitudinally with the bevelled face at one side of the cutting edge of the blade bearing against one of the sloping walls of the recess 19 of the abrading block. A number of strokes may be imparted to the carrier and the carrier then rotated to move it into engagement with the other rib 17 so that the other bevelled face of the blade will be brought into engagement with the abrading block or a rotary movement imparted to the carrier at the termination of each reciprocatory movement by turning the wrist before again imparting longitudinal movement to the carrier. The angular relation of the ribs 17 to the groove 19 insures flat contacting engagement of the bevelled faces of the blade with the walls of the groove 19 and therefore, the cutting edge of the blade will be properly sharpened. Since contact of the flared portions 28 with the backing strip of the blade limits upward movement of the blade through the slot 26 there will be no danger of the cutting edge of the blade being dulled by improper contact with the abrading block. As the blade is sharpened, as it is withdrawn from

the handle, it will have a good cutting edge when applied to the guard.

From the foregoing description of the construction of our improved device, the operation thereof and the method of applying the same to use will be readily understood. It will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to, without departing from the spirit or sacrificing any of the principles of the invention.

Having thus described the invention, what is claimed is:

1. In a razor, a handle formed with a chamber opening through the rear end of the handle, a sharpening element extending longitudinally in said chamber against a portion of the walls thereof and formed with a longitudinally extending groove having converging walls, and a blade carrier inserted into the chamber through the open rear end thereof and bearing against a portion of the walls of the chamber opposite the sharpening element with its blade holding portion presented towards the sharpening element whereby a blade carried by the carrier will have its cutting edge engaged in the groove of the sharpening element, said carrier being slideable longitudinally in the chamber for reciprocating a blade in sharpening engagement with the sharpening element, the carrier being also oscillatable in the chamber for disposing the cutting edge of the blade in engagement with a selected side wall of the groove in the sharpening element.

2. In a razor, a handle formed with a chamber opening through the rear end thereof, walls of the chamber being provided at opposite sides thereof with sets of longitudinally extending ribs, the ribs of each set being spaced from each other circumferentially thereof, a sharpening element extending longitudinally in said chamber and secured against the walls between the ribs of one set to brace the sharpening element against transverse movements in the chamber, said sharpening element being formed with a longitudinally extending groove in its exposed face, and a blade carrier inserted into the chamber through the open rear end thereof, said carrier bearing against walls of the chamber between the other set of ribs with its blade carrying portion facing the sharpening element whereby the cutting edge of a blade will engage the sharpening element in the groove thereof, said blade carrier being slideable longitudinally in said chamber and oscillatable therein between the last mentioned ribs, the last mentioned ribs serving to guide reciprocation of the blade carrier in the chamber and as means for limiting oscillation of the carrier whereby the cutting edge of a blade may be disposed in engagement with a selected side wall of the groove in the sharpening element.

3. In a razor, a handle formed with a longitudinally extending chamber open at its rear end and oval in cross section, a block of abrading material extending longitudinally in said chamber against a wall at a side thereof, and a blade carrier slideable into and out of the chamber through the open end thereof and oscillatable in the chamber against a portion of walls of the chamber opposite the abrading block, said carrier consisting of a hollow body formed of resilient material and open at one end, a head at the other end of said body fitting snugly in the open end of said body fitting snugly in the open end of the handle when the blade carrier is thrust into the chamber with a portion projecting from the handle and constituting a hand hold for the carrier, said body being formed with a longitudinally extending slot and carrying inwardly directed jaws at opposite sides of the slot for gripping a blade and holding the blade diametrically of the body with its cutting edge bearing against the abrading block, blade engaging fingers at the open end of said body, and resilient tongues in the body opposite the slot for engaging the inner edge of a blade and urging the blade outwardly through the slot to hold its cutting edge against the abrading block.

4. In a razor, a handle formed with a longitudinally extending chamber open at its rear end and oval in cross section, a block of abrading material extending longitudinally in said chamber against a wall at a side thereof, and a blade carrier slideable into and out of the chamber through the open end thereof and oscillatable in the chamber against a portion of walls of the chamber opposite the abrading block, said carrier consisting of a hollow body formed of resilient material and open at one end, a head at the other end of said body fitting snugly in the open end of the handle when the blade carrier is thrust into the chamber with a portion projecting from the handle and constituting a hand hold for the carrier, said body being formed with a longitudinally extending slot and having an internal abutment at the inner end of the slot, fingers at the open end of the body for holding a blade in the body with one end engaging the abutment and its cutting edge projecting through the slot for contact with the abrading block, inwardly extending gripping plates at opposite sides of the slot, and resilient tongues in the body opposite the slot for engaging the inner edge of a blade and urging the blade outwardly through the slot to hold its cutting edge against the abrading block.

5. In a razor, a handle formed with a chamber opening through the rear end of the handle, a sharpening element in said chamber, a blade carrier inserted into the chamber through the open rear end thereof with a portion closing the rear end of the chamber and projecting rearwardly from the handle to provide a hand hold, said blade carrier being slideable longitudinally in said chamber for reciprocating a blade in sharpening contact with the sharpening element and shiftable transversely in the chamber for presenting the blade in predetermined angular relation to the sharpening element, and means for limiting transverse shifting of the holder.

6. In a razor, a handle having a chamber formed therein opening through the rear end of the handle, a sharpening element mounted in said chamber and extending longitudinally in the chamber against walls thereof, a blade carrier inserted into said chamber through the open rear end thereof and slideable longitudinally therein, the carrier being shiftable transversely in the chamber for presenting the blade to the sharpening element in predetermined angular relation thereto, the distance between the sharpening element and the opposed portion of walls of the chamber being greater than the depth of a blade to be sharpened whereby the carrier with a blade applied thereto may be inserted into the chamber with the cutting edge of the blade bearing against the sharpening element and actuated to sharpen the blade, and means carried by walls of said

- chamber at opposite sides of the carrier for limiting shifting movement of the carrier transversely of the chamber, said means also serving to guide sliding movement of the carrier.
5. 7. In a razor, a handle having a chamber formed therein opening through the rear end of the handle, a sharpening element mounted in said chamber and extending longitudinally thereof, a blade carrier inserted into the chamber through the open end thereof and being slidable longitudinally in the chamber and shiftable circumferentially thereof, the distance between the sharpening element and the opposed portion of the walls of the chamber being greater than the depth of a blade to be sharpened whereby the carrier with a blade applied thereto may be inserted into the chamber through the open rear end thereof with the cutting edge of the blade bearing against the sharpening element and actuated to sharpen the blade, and longitudinally extending ribs carried by walls of the chamber for engaging sides of the carrier and serving to limit transverse shifting movement of the carrier, said ribs also serving to guide longitudinal movement of the carrier.
8. In a razor, a handle formed with a chamber opening through the rear end of the handle, a sharpening element removably mounted in said chamber, a blade carrier inserted longitudinally of the handle through the open rear end of the chamber, said carrier being shiftable transverse-
- 10
- 15
- 20
- 25
- 30

ly for presenting a blade in selected angular relation to the sharpening element and being also reciprocatory longitudinally therein for supporting a blade in engagement with the sharpening element and imparting reciprocating movement to the blade relative to the sharpening element, and means carried by walls of the chamber for limiting transverse movements of the carrier and guiding reciprocatory movement.

9. In a razor, a handle formed with a chamber opening through the rear end of the handle, means in said chamber for sharpening a razor blade, having blade engaging surfaces in angular relation to each other, and means for carrying a razor blade and supporting the blade diametrically of the chamber with its edge in operative engagement with the sharpening means, said blade carrier with a blade carried thereby being adapted for insertion into the chamber through the rear end thereof and reciprocatory longitudinally in the chamber with the blade in engagement with a selected surface of the sharpening means, the carrier being shiftable transversely in the chamber for disposing the blade in engagement with a selected surface of the sharpening means, and means projecting inwardly from walls of the chamber at opposite sides of the carrier for limiting transverse shifting of the carrier and guiding reciprocatory movement of the carrier.
